UNITED STATES PATENT OFFICE.

CARLOS E. DUNSHEE, OF CHICAGO, ILLINOIS.

LUMBER-PILER.

SPECIFICATION forming part of Letters Patent No. 321,348, dated June 30, 1885.

Application filed February 2, 1885. (No model.)

To all whom it may concern:

Be it known that I, CARLOS E. DUNSHEE, of the city of Chicago, in the county of Cook and State of Illinois, have invented certain new and useful Improvements in Lumber-Pilers, of which the following is a description, reference being had to the accompanying drawings, in which—

Figure 1 is a side elevation of my improved lumber-piler. Fig. 2 is an end view of the same. Fig. 3 is a top view of one of the cylinders, hereinafter described, which are mounted upon the car. Fig. 4 is a cross-section of one of the upright posts, and Fig. 5 is a detailed view of the operating devices attached to the central upright.

The piling of lumber, especially in lumber-yards where, because of lack of ground, the piles must be made very high, is a difficult and expensive operation, and adds very materially to the cost of the lumber.

The object of my invention is to provide a novel combination of mechanism whereby lumber may be rapidly and regularly piled and to any reasonable height.

To this end it consists in the construction and combination of parts hereinafter described, and definitely pointed out in the claims.

In the drawings, A A' A² A³, &c., represent upright supports or posts. These uprights I prefer to make in parts or sections of about ten feet in length. The uprights A A', &c., are six in number, three in front and three behind. The transverse distance between the posts I prefer to make about twelve feet and the longitudinal distance about sixteen feet; but these distances are not material, and depend upon the size of the lumber it is desired to handle. The sections a a are joined together by means of the metal caps a' a'', which are bolted securely to the ends of said sections, as shown. When the posts are placed in position, they are secured by the braces B B', &c., bolted or otherwise fastened thereto.

The inner face of each of the posts A A', &c., is provided with a T-shaped groove, a'', extending from top to bottom. Within these grooves play the ends of the cross-beams C C C, the center beam being necessarily bent, as shown in Fig. 2, which beams extend transversely across from one upright to the other.

D D represent rails or tracks, which are secured to said cross-beams C at appropriate distances from the uprights A A', &c.

Fixed to each of the uprights A A', &c., near the foot thereof, are bearings in which the transverse shafts E revolve.

Mounted upon each of the shafts E, near the inner faces of each of the uprights A A', &c., are the two drums e', as shown in Fig. 2, and upon one of the outer ends of said shaft E are mounted the beveled gear-wheels e. The shaft F is mounted at right angles to the shaft E in bearings f, attached to each of the three front posts, as shown in Fig. 1, which shaft F bears the beveled gear-wheels f' f' f'', which mesh each with one of the gears e upon the shafts E, so that a revolution of one shaft causes a like revolution of all.

At the top of each upright A A', &c., are fixed the sheave-pulleys G G' G'', &c., as shown. A wire rope or cable, g, is secured to each end of each of the cross-beams C, passes up over the sheave G, and then down, and is fastened to the drum e'.

The means for revolving the shafts E are preferably secured to the middle upright A, and consist in the following to wit: Within bearings h h', attached to said upright A, is mounted the shaft H. This shaft H has mounted upon it the ratchet-wheel h'', the sprocket-wheel h³, and the crank or driving wheel h'. Upon the shaft E, mounted upon said upright A, is a sprocket-wheel, e², which is connected with the sprocket-wheel h³ by the drive-chain J. It is evident, therefore, that a revolution of the shaft H, whether imparted by hand or in whatever manner imparted, causes, through the instrumentality of the sprocket-wheels h³ and e² and drive-chain J, a revolution of the transverse shaft E, to which said sprocket-wheel e² is attached, and this, as before explained, revolves the two other transverse shafts E. By these means the drums e' wind up the ropes g, and thus raise the cross-beams C and tracks D to any desired height, and the ratchet h'' holds the same in that position.

Upon the tracks D D a car, K, is run, as hereinafter described. This car K consists of a light frame mounted upon trucks, as shown.

The cylinders M M' are mounted in bearings upon the frame of the car at each end thereof.

These cylinders $M M'$ are mortised, as shown in Fig. 3, and through these mortises the bent bars or hooks m pass and are sustained by the bolt-heads m' at their upper ends. Attached 5 rigidly to the upper sides of the cylinders M M' are the arms m^2 and m^3 , respectively.

At or near the center of the car a transverse shaft is mounted in bearings l , which shaft has fixed rigidly at or near its center the arm L , 10 extending on both sides of said shaft. The arm l' is also fixed to said shaft near the end thereof, as shown. The arms m^2 m^3 are connected with the opposite ends of the arm L in such a manner, as shown, that when the shaft 15 to which the arm L is attached is revolved the two cylinders M M' are each revolved in the opposite direction.

Attached to the side of the frame of the car K is the bent arm k , which supports a swiv- 20 el pulley, k' .

Bolted to the rail D upon its under side and inclining away from the rail, so as not to interfere with the movement of the car K , is a bent arm, N , also bearing a swivel-pulley n .

25 A cord, n' , is fastened to the arm l' and passes over the pulleys k' and n and down within reach of the operator, who stands by the central upright A .

The arms $P P'$ are bolted to the under side 30 of the rail D , and bear the sheave-pulleys p p' , respectively. The ropes p^2 and p^3 are attached to opposite ends of the car K , as shown, and pass over the pulleys p and p' down within reach of the operator.

35 The depending arms R are fastened to the cross-beam r of the car K , slightly upon a slant to the perpendicular, and shape the end of the pile of lumber.

The operation of the device is as follows: 40 The lumber which it is desired shall be piled is laid on horses, one course or more at a time, between the posts A and A' . The cross bars $C C C$ are now allowed to descend, carrying with them the tracks $D D$ and car K . As the 45 car is thus descending the cord n' is pulled upon, thereby turning the cylinders $M M'$. This turns back the hooks m , so they will clear the ends of the boards. When below the level of the boards the cord is released and the hooks 50 m are permitted to resume their normal position, as shown in Fig. 1, below the boards, which they will do by reason of their own weight. The power is now applied to the crank or driving-wheel, and, as before explained, the drums e wind the ropes g about themselves, thereby elevating the cross-beams C , tracks D , and car K , carrying the course of boards. When they are at the proper height, so that the boards are above the level of the 55 pile of lumber, the cord p^3 is pulled upon, which pulls the car over the lumber-pile until the arms R strike against the face of the pile. Then the operator pulls upon the cord n' , which, as before described, turns up the hooks m and 60 drops the boards upon the pile. The cord p^2 65

is pulled upon by the operator, which drives the car back to the position as shown in Fig. 1, when the operation just described may be repeated until the pile has reached the desired height.

The bearings in which the roller M' is mounted may be moved along the frame of the car as desired, and bolted at any point so as to take in any length of lumber.

Having thus described my invention, what I 75 claim as new, and desire to secure by Letters Patent, is—

1. In a lumber-piler, the combination of upright supports, sheaves mounted thereon at or near their tops, transverse shafts mounted 80 thereon near their feet, drums mounted upon said transverse shafts, and a longitudinal shaft mounted in bearings attached to said upright supports and geared to said transverse shafts, with transverse cross-beams, tracks mounted 85 upon said cross-beams, cables attached to said cross-beams, passing over said sheaves, and attached to said drums, and means for rotating said shafts, substantially as and for the purpose set forth.

2. In a lumber-piler, the combination of vertically-adjustable tracks and a car adapted to run on said tracks, and mechanism whereby the car is moved along said tracks, with depending hooks mounted upon said car and 95 means for swinging said hooks in contrary directions, substantially as and for the purpose set forth.

3. In a lumber-piler, the combination, substantially as set forth, of vertically-adjustable 100 tracks, a car adapted to run upon said tracks, two mortised cylinders mounted in bearings upon said car, hooks which operate in said mortises, the arms M^2 M^3 , attached to said cylinders, a transverse shaft mounted near the 105 middle of said car, the arms L l , attached thereto, rods connecting the arms M^2 M^3 and arm L , the arm k , and swivel-pulley k' , with the arm attached to the track, the swivel-pulley n , and cord n' , for the purpose specified. 110

4. In a lumber-piler, the combination of vertically-adjustable tracks and a car adapted to run on said tracks with the pulleys p p' , fastened to the under side of said tracks, and the cords p^2 p^3 , attached to said car and passing 115 over said pulleys, substantially as described, and for the purpose set forth.

5. In a car adapted to run on vertically-adjustable tracks, the combination of two mortised cylinders mounted upon said car, and hooks operating in said mortises, and means for producing a partial revolution of said cylinders in opposite directions, with depending arms attached to one end of said car, substantially as and for the purpose set forth.

CARLOS E. DUNSHEE.
